UNITED STATES PATENT OFFICE.

ERNEST H. HORN, OF WATERBURY, CONNECTICUT, ASSIGNOR TO THE WATERBURY CLOCK CO., OF WATERBURY, CONNECTICUT, A CORPORATION.

WATCH.

No. 926,329.

Specification of Letters Patent.

Patented June 29, 1909.

Application filed November 25, 1907. Serial No. 403,710.

To all whom it may concern:

Be it known that I, ERNEST H. HORN, a citizen of the United States, residing at Waterbury, in the county of New Haven and State of Connecticut, have invented a new and useful Improvement in Watches; and I do hereby declare the following, when taken in connection with the accompanying drawings and the characters of reference marked thereon, to be a full, clear, and exact description of the same, and which said drawings constitute part of this specification, and represent, in—

Figure 1 a view in front elevation of a watch constructed in accordance with my invention, with the face of the case removed. Fig. 2 a broken view of the watch partly in front elevation and partly in vertical section, a portion of the front movement-plate being broken away. Fig. 3 a detached view in side elevation of my improved one-piece crown stem. Fig. 4 a reverse plan view thereof. Fig. 5 a detached view in side elevation of the winding and setting stem, with the setting wheel and the winding ratchet mounted upon it. Fig. 6 a reverse plan view showing the lower end of the winding and setting stem and the lower face of the winding ratchet, the stem being upset to retain the ratchet in place and to form a bearing surface of small area for contact with the winding-and-setting stem spring. Fig. 7 a sectional view on the line *a—b* of Fig. 5 looking upward and showing how the winding ratchet is loosely mounted upon the squared lower end of the winding-and-setting stem. Fig. 8 a detached reverse plan view of the bridge from which the winding-and-setting stem has been removed to show the winding pinion the lower face of which is formed with teeth for engagement by the winding ratchet. Fig. 9 a view of the same parts in vertical central section on the line *c—d* of Fig. 8.

My invention relates to an improvement in stem-winding and stem-setting watches, the object being to reduce the number of parts to the minimum and to secure for the winding and setting functions of a cheap watch, the smoothness and quietness of operation characteristic of the winding and setting functions of watches of high grade.

With these ends in view, my invention consists in a watch having certain details of construction and combinations of parts as

will be hereinafter described and pointed out in the claims.

In carrying out my invention as herein shown, I employ a one-piece crown stem consisting of a body 2 having its upper end formed with threads 3 and its lower end formed with a beveled retaining flange 4 and a driving edge 5. The threads 3 provide for the attachment of the crown 6 which may be of any ordinary construction. The retaining flange 4 enters a counter-bore 7 in the lower end of the pendant 8 and limits the outward movement of the stem and prevents it from being pulled out of the said pendant which is formed with a chamber 9 for the reception of a spring 10 encircling the body 2 of the stem and exerting a constant effort to lift the stem and its crown into their normal positions in which they are shown in Fig. 2. The driving edge 5 enters a slot 11 extending diametrically across a coupling head 12 formed integral with and located at the upper end of a winding-and-setting stem 13 which, though made independent of the crown-stem 2, constitutes a virtual extension thereof.

In many watches, particularly those of high grade, the winding and setting stem is made in one piece and not, as it were, broken into two pieces coupled together as in the construction now being described. My improved crown-stem 2 being made in one piece is simple, durable, cheap and not liable to derangement.

The winding-and-setting stem 13 is formed just below its slotted coupling head 12 with a shoulder 14 upon which the setting wheel 15 is staked, the upper face of this wheel being brought to a bearing upon the lower face of the head 12. At its lower end, the stem 13 is squared as at 16 for the reception of a winding ratchet 17 which is formed with a square hole 18 just enough larger than the squared portion 16 of the stem to permit the ratchet to have a slight rotary movement with respect to the stem 13 the rotation of which, however, it must partake. Furthermore the squared portion 16 is made a trifle longer than the depth of the ratchet 17 to provide for a slight upward and downward movement of the ratchet with respect to the stem 13. In this way the ratchet is nonrotatably mounted upon the stem 13 and at the same time made loose enough or flexible enough in its connection therewith to permit its

ratchet teeth 18^a to accommodate themselves readily and slide into and out of engagement with the minimum of jar and friction with the face teeth 19 formed upon the 5 lower face of the winding pinion 20 which is mounted so as to turn freely in the bridge 21 the upper face of the pinion 20 being formed with a sleeve 22 which projects upward through the bridge as shown in Fig. 9. The 10 central bore 24 of the pinion 20 receives the winding-and-setting stem 13 which is free to move up and down, as well as to rotate within the pinion 20. For securing the ratchet 17 upon the squared portion 16 of the stem 13, the projecting lower end of the squared portion 16 is upset to form the retaining head 25; while to provide a bearing of small area for the winding-and-setting-stem spring 26 the central portion of the head 25 is raised to 20 form a small contact surface 27 which reduces the frictional area for engagement by the spring 26, to the minimum:

The operation of watches of the type being described is so well understood that it will be 25 sufficient for me to state that the springs 10 and 26 normally maintain the stems 2 and 13 at the limit of their outward movement at which time the winding ratchet 17 couples both stems with the winding pinion 20 which 30 is always in mesh with the intermediate winding wheel 28 which in turn is always in mesh with the main winding wheel 29. When, however, the stems 2 and 13 are crowded inward against the tension of the 35 springs 10 and 26 by pressure upon the crown 6, the teeth 18^a of the winding ratchet 17 are forced out of engagement with the teeth 19 of the winding pinion 20 so as to move the setting wheel 15 inward into engagement 40 with the dial wheel 30 which in turn meshes into the dial wheel 31 of the dial work.

By making the crown stem 2 in one piece the number of parts and the number of operations is reduced, and a simpler, more durable and more reliable device secured, while 45 by loosely mounting the ratchet 17 upon the winding-and-setting stem the ratchet is made self-accommodating so to speak, whereby noise and wear are reduced.

50 I claim:

1. In a stem-winding and stem-setting watch, the combination with the pendant thereof, of a one-piece crown-stem located therein, projecting at its threaded outer end therefrom, formed at its inner end with an annular retaining-flange coacting with the inner end of the pendant and also formed with a driving-edge projecting from the center of the inner face of the said flange; a 55 crown applied to the threaded projecting outer end of the said stem, an independently formed winding-and-setting stem adapted at its outer end to receive the said driving-edge of the crown-stem, a setting-wheel fixed upon

the outer end of the winding-and-setting 65 stem, and a winding ratchet loosely mounted upon the inner end of the said winding-and-setting stem.

2. In a stem-winding and stem-setting watch, the combination with the pendant 70 thereof, of a crown-stem mounted therein, projecting at its threaded outer end therewith, provided at its inner end with an annular retaining-flange, and also formed with a driving-edge centrally depending from 75 the inner face of the said flange; a crown applied to the threaded projecting outer end of the said stem, an independently formed winding-and-setting stem having at its outer end a slotted coupling-head for the reception 80 of the said driving-edge, a setting wheel fixed to the winding-and-setting stem and bearing against the lower face of the said coupling-head, a winding-ratchet loosely mounted upon the inner end of the said stem, and 85 means exerting a constant effort to move the two stems outward.

3. In a stem-winding and stem-setting watch, the combination with the pendant 90 thereof, of a crown-stem located therein and projecting outward therefrom, formed at its inner end with an annular retaining-flange engaging with the inner end of the said pendant, and also formed with a driving-edge depending from the center of the inner face of the 95 said flange, a crown applied to the projecting outer end of the said crown-stem, an independently formed winding-and-setting stem adapted at its outer end to receive the said driving-edge, a setting-wheel rigidly secured 100 to the outer end of the winding-and-setting stem, a winding-ratchet loosely mounted upon the inner end of the said winding-and setting-stem, a bridge, a winding-pinion mounted to turn loosely therein and carrying face-teeth 105 coacting with the said winding-pinion, and a spring engaging with the extreme inner end of the winding-and-setting stem for moving the two stems outward.

4. In a stem-winding and stem-setting 110 watch, the combination with a crown stem, of a winding-and-setting stem made independent thereof but normally coupled therewith and having its lower portion squared 115 and its extreme lower end formed with a retaining-head having a bearing-surface, a spring bearing upon the said surface and exerting a constant effort to move the two stems outward, and a winding ratchet mounted upon the squared portion of the 120 winding-and-setting stem.

In testimony whereof, I have signed this specification in the presence of two subscribing witnesses.
